M. BLUMENTHAL.

MOLD FORM.

APPLICATION FILED MAR. 19, 1917.

1,238,384.

Patented Aug. 28, 1917.

Inventor

Maurice Blumenthal,

By his Attorney

Edgar Dale & Co.

UNITED STATES PATENT OFFICE.

MAURICE BLUMENTHAL, OF BROOKLYN, NEW YORK.

MOLD-FORM.

1,238,384.

Specification of Letters Patent. Patented Aug. 28, 1917.

Application filed March 19, 1917. Serial No. 155,653.

To all whom it may concern:

Be it known that I, MAURICE BLUMENTHAL, a citizen of the United States, and residing at Brooklyn, in the county of Kings and State of New York, have invented certain new and useful Improvements in Mold-Forms, of which the following is a specification, such as will enable those skilled in the art to which it appertains to make and 10 use the same.

This invention relates to mold forms, and particularly to devices of this class designed for use in-making electric cable and other conduits in or of cement, concrete or similar 15 material, and the object thereof is to provide an improved mold form of the class and for the purpose specified whereby conduits of the class specified and intended for any desired purpose may be quickly, economically 20 and easily formed or constructed, and with this and other objects in view the invention consists in a mold form or forms of the class specified, constructed and adapted to be used as hereinafter described and 25 claimed.

The invention is fully disclosed in the following specification, of which the accompanying drawing forms a part, in which the 30 separate parts of my improvement are designated by suitable reference characters in each of the views, and in which;—

Figure 1 is a longitudinal sectional view showing one step in the process of using my improved mold form or forms in making 35 concrete conduits;

Fig. 2 a similar view showing another step of said process;

Fig. 3 a section on the line 3—3 of Fig. 1;

Fig. 4 a sectional longitudinal view of 40 one of my improved mold forms;

Fig. 5 a section on the line 5—5 of Fig. 4; and,

Fig. 6 a view similar to Fig. 5 but showing a modification.

In the practice of my invention, I provide a mold form *a* shown in Figs. 1, 5 and 6, and which consists of a metal tube of any desired length and any preferred transverse dimensions, and which is made up of 45 two similar opposite longitudinal parts *a*² and two other similar longitudinal parts *a*³, and the parts *a*² are tapered from one end *a*⁴ of the tube to the other end *a*⁵ of the tube, and the parts *a*³ are similarly tapered in the opposite direction, and the parts *a*² are rigidly connected by transverse brace or other members *a*⁶, in any desired manner, to form what I call a wedge or key member *a*⁷. The side portions *a*² of the wedge member *a*⁷ and the corresponding longitudinal side 60 members *a*³ of the tubular form are preferably connected as shown in Fig. 5, in which the side edge portions of the parts *a*³ abut against the side edge portions of the parts *a*², and the parts *a*² are provided at 65 their opposite ends with lugs or ears *a*⁸ which overlap the parts *a*³, and through which are passed screws *a*⁹ which are screwed into the parts *a*³, and whereby the wedge member *a*⁷ formed by the parts *a*² 70 and the parts *a*³ of the tubular form are rigidly connected.

In Figs. 1, 2, and 3 I have indicated a process of using two of my improved mold forms in making conduits in cement, concrete and similar material, or in making concrete or cement conduits of the class specified, and in said figures I have also shown at *b* a section of earth or street in which is dug or formed a trench *b*² and, in 80 the practice of my invention, I place in the trench a mold box *c* preferably consisting of side members *c*² and end members *c*³ and *c*⁴, and the parts of the mold box may be connected in any desired way so as to be 85 quickly and easily taken down or knocked down, and set up again for use, whenever desired.

The end portions *c*³ and *c*⁴ of the mold box *c* are provided with apertures *c*⁵, and the form or forms *a* are passed through said mold box and through said apertures, as shown in Fig. 1, after which concrete or similar material *b* is poured into the mold box, and conduits *c*⁶ are formed in the concrete, and when this concrete has had time to set or become hard or partially so, the wedge member or members *a*⁷ of the forms are drawn out in the direction of the arrow *x*, the screws *a*⁹ having been first withdrawn 100 after which the parts *a*³ of the forms may be easily taken out as will be readily understood, after which the parts *a*³ of the forms are again connected and the end portions *a*⁵ thereof are inserted into the conduits *c*⁶ 105 in the section of concrete first built up, after which the box *c* is placed in position with the exception of the end portion *c*⁴ thereof, and as indicated in Fig. 2, after which said mold box is again filled in with concrete, and 110

this process is continued or repeated as long as is desirable or necessary, and concrete conduits of the class and for the purpose specified may thus be quickly and easily 5 formed by means of my improved mold form or forms, any desired number of which may be employed in a single mold box or section, and it will also be understood that the mold form or forms may be of any de- 10 sired length and of any desired transverse dimensions, according to the use for which the conduits are intended, and conduits made in this manner may be used as electric cable or wire conduits, or as sewer or drainage conduits, or for any other desired purpose.

In order to be able to pull out the wedge or key member a^7 of the form, as hereinbefore described, any suitable pulling device 20 or means may be connected with one of the transverse brace members a^6 , or I may form in the larger end portions of the parts a^6 of the wedge or key member holes d with which may be connected any suitable device 25 for performing said operation.

In Fig. 6 of the accompanying drawing, I have shown a modified construction of the mold form a in which the separate parts a^2 and a^3 are abutted and provided with an interlocking rabbet groove construction e , and with this exception the construction and operation will be the same as that shown in Figs. 4 and 5, and one of the parts a^3 , the bottom part when the mold form or forms 35 are in use, is provided with a longitudinal rib or fin portion f by which a draining groove g is formed in the bottom of the conduit or conduits c^6 .

Although I have shown and described my 40 improved mold form as circular in form in cross section, it will be understood that this cross sectional shape is not absolutely necessary, and other shapes or forms may be employed, and changes in and modifications of 45 the construction herein described may be made, within the scope of the appended

claims, without departing from the spirit of my invention or sacrificing its advantages.

Having fully described my invention, what I claim as new and desire to secure by Letters Patent, is:—

1. A tubular mold form composed of four separate similar longitudinal parts, of which two oppositely arranged parts are tapered from one end to the other and connected transversely to form a wedge or key device and the other oppositely arranged parts being tapered in the opposite direction. 55

2. A tubular mold form composed of four separate longitudinal parts, of which two oppositely arranged parts are tapered from one end to the other and connected to form a wedge or key device and the other oppositely arranged parts being tapered in the opposite direction, said parts being detachably connected. 60

3. A tubular mold form of the class specified, composed of four longitudinal similar parts, two of which are tapered from one end of the mold device to the other and the other two tapered in the opposite direction, one of said parts being provided on the outer side thereof with a longitudinal rib or fin. 70

4. A tubular mold device composed of four similar longitudinal parts, of which two opposite parts are tapered from one end to the other of the mold device and connected to form a key or wedge, the other two parts being tapered in the opposite direction and all of said parts being detachably connected and one of said parts being provided with a longitudinal rib or fin on the outer side thereof. 75

In testimony that I claim the foregoing 85 as my invention I have signed my name in presence of the subscribing witnesses this 10th day of March 1917.

MAURICE BLUMENTHAL.
